UNITED STATES PATENT OFFICE

93,101

DESIGN FOR A CABINET FOR WASHING MACHINES OR THE LIKE

Lurelle Guild, Darien, Conn., assignor to Electric Household Utilities Corporation, Cicero, Ill., a corporation of Illinois

Application June 12, 1934, Serial No. 52,153

Term of patent 14 years

To all whom it may concern:

Be it known that I, LURELLE GUILD, a citizen of the United States, residing at Darien, in the county of Fairfield and State of Connecticut, have invented a new, original, and ornamental Design for a Cabinet for Washing Machines or the like, of which the following is a specification, reference being had to the accompanying drawing, forming part thereof.

In the drawing, Fig. 1 is a front view and Fig. 2 is a side view of a cabinet for washing machines or the like, illustrating my new design.

I claim:

The ornamental design for a cabinet for washing machines or the like, as shown.

LURELLE GUILD.
